UNITED STATES PATENT OFFICE.

EARL H. RICHARDSON, OF ONTARIO, CALIFORNIA.

ELECTRIC LAUNDRY-IRON.

No. 866,810.

Specification of Letters Patent.

Patented Sept. 24, 1907.

Application filed October 10, 1906. Serial No. 338,234.

To all whom it may concern:

Be it known that I, EARL H. RICHARDSON, a citizen of the United States, residing at Ontario, in the county of San Bernardino and State of California, have invented 5 new and useful Improvements in Electric Laundry-Irons, of which the following is a specification.

This invention relates particularly to laundry irons which are heated by means of an electrical current which is passed through a resistance detachably secured 10 to the body of the iron; and a main object of this invention is to provide a laundry iron in which the electric circuit is automatically opened when the temperature of the iron reaches a predetermined point.

Heretofore in electric laundry irons and particularly 15 in the specific constructions illustrated and described in a former United States Letters Patent issued to me on electric laundry irons, No. 809,529 and on my allowed application entitled Electric heating unit, S. N. 292,409, no provision is made when the iron is out of 20 service, for automatically opening the circuit when the switch plug is accidentally left in circuit.

It often happens when the plug is accidentally left in circuit for a long time, when the iron is out of service, that the temperature of the iron increases to such a high 25 degree as to warp the body and melt the heating element to such an extent, as to render the further use of the iron impracticable without first renewing the parts rendered useless. It is with a view of rendering the occurrence of such accidents practically impossible, that this 30 invention has been conceived.

Another object of this invention is to combine the heating elements with the base of the iron so as to render the whole easily transportable.

Another object is to provide for the complete insulation of the cover of the iron from the body so as to prevent any upward radiation.

A further object is to provide means for maintaining at all times when the cover is secured to the body a perfect electrical contact, and at the same time to provide 40 means for its simple adjustment to the body.

I accomplish these objects by means of the device described herein and illustrated in the accompanying drawings in which:

Figure 1.— is a side elevation of the iron showing it 45 supported by the stand secured thereto. Fig. 2.— is a plan view of the iron with the cover removed. Fig. 3.— is a central vertical section taken on line 3—3 of Fig. 2 with the cover in section and secured to the body. Fig. 4.— is an enlarged sectional detail of one of the 50 terminals taken on line 4—4 of Fig. 2. Fig. 5.— is a cross sectional detail taken on line 5—5 of Fig. 2. Fig. 6.— is a rear elevation of the iron partly in section.

Referring to the drawings, the body of the iron 5 is preferably composed of a flat sole 6 of sufficient thickness to give it weight, and preferably formed integral therewith and on the top thereof are triangularly dis-

posed lugs 7 and 8. These lugs are provided with recesses 9 and 10 which extend downwardly to the top of the sole of the iron and are transversely joined at the heel of the iron by a rib 10', the purpose of which is 60 to strengthen the body and to prevent its warping. Arranged within each recess is a heating element, which comprises a core 11, that is preferably rectangular in cross section. The respective ends of the core within the corner portions 12 and the toe portion of the body, 65 and each end 13 is of a width which snugly fits in the recess, so that as perfect a contact as possible is formed between the solid metal of the body and the ends of the core. In order to allow for the expansion of the cores when heated, as it is preferred to construct the body of 70 iron, and the cores of copper, the cores are made slightly shorter than the lengths of the recesses. A portion of each core, extending between its ends 13 is reduced in cross section so as to accommodate its insulation and winding. 75

In assembling the heating elements in the iron, the reduced portion of each core is wrapped with a sheet of mica 14 to insulate all of its faces. Wire 15 is then wound over the mica and the coils are slightly spaced apart, to prevent short circuiting. The recesses in the 80 lugs with the exception of the end walls are then lined with mica 16 and the core thus prepared is slipped into its recess forming a snug fit, giving a flat contact between the mica 16 at all points within the walls of the recess. 85

The inner side walls of the recesses are provided near each end with slots 17 which open into the central cored out portion 18 and the forward end of the wires are carried from the cores out through the slots and connected together as shown. A small sheet of mica 19 is slipped 90 under the wires so connected, the ends resting at the top of the lugs 7 and 8 so as to prevent short circuiting. The rear end wires are likewise brought through the rear slots 17 and connected to the respective terminals or interior binding posts 20 and 21. These binding 95 posts are preferably secured to the rib 10' and are insulated therefrom by washers 22 of mica or other non-conducting material and the rear end of the wires of the cores are connected thereto. Secured to the outer ends of these binding posts 20 and 21 in any suitable 100 manner are thermic fuses 23 and 24 which are adapted when the cover is secured to the body of the iron to contact with the chamfered inner ends of the exterior binding posts 25 and 26 which are secured to the rear end of the cover 27 and are insulated therefrom by washers 28, of mica or other non-conducting material. Secured to the outer end of these exterior binding posts are contact clips 29 and 30 which are adapted to be engaged by a switch plug 31 having terminals (not shown) for contacting with the clips 29 and 30. The forward 110 end of the triangularly disposed lugs 7 and 8 inclines outwardly and downwardly as at 32 to the sole of the

iron, and the outer end of the cover 27 is provided with a similar incline 33 which is adapted when the cover 27 is secured in position on the body of the iron, to draw the inner ends of the exterior binding posts into perfect contact with the fuses secured to the outer end of the interior binding posts secured to the rib 10. The cover 27 is detachably secured to the body of the iron by screws 34 and is provided with the usual bail 35, to which handle 36 is secured. The interior of this 10 cover is lined on its inner face and sides with sheets of asbestos, or other heat resisting material 37 to prevent any upward radiation, and its lower edge rests on a thick layer of asbestos 38 which is designed to rest on the top of the body of the iron, the inner portion being 15 cut away so as to accommodate the triangular shaped lugs 7 and 8, and the outer portion trimmed flush with the sides of the iron.

It will be noted from the foregoing description that I have produced a laundry iron in which any danger 20 from overheating when the switch plug is accidentally left in circuit is practically eliminated, as the moment the iron reaches a certain temperature it will immediately melt one of the fuses connected to the interior terminals, thereby opening the electrical circuit, the 25 melted fuse falling into a pocket 39 formed by the rib 10 and the inner edge of asbestos 38, thus insuring complete protection against melting the heating elements or injuring the iron. The inclines formed on the outer ends of the lugs and on the inside outer end of the 30 cover are so formed that when the cover is secured to the body of the iron, it will tend to pull the cover forwardly thus insuring an absolutely perfect contact between the interior and exterior binding posts.

It will also be noted that by forming the body of the 35 iron in a small and compact mass that transportation is facilitated when the replacement of parts becomes necessary by reason of long and continued use.

The entire insulation of the inner side of the cover 40 renders the utilization of every heat unit absolutely possible and at the same time renders the cover of the iron comparatively cool.

It will be further noted that I have produced a laundry iron that is comparatively simple in construction and effective in operation and one in which the parts 45 are few and are readily assembled.

Having described my invention what I claim as new and desire to secure by Letters Patent is:—

1. A device of the class described, comprising a body 50 having a recess; a wire wound core detachably secured in said recess; binding posts secured to said body, the ends of the wire on the core being connected with the binding posts; a cover detachably secured to said body; binding posts secured to said cover, said binding posts adapted to connect with the first named binding posts through fuses; and fuses interposed between said binding posts.

2. An electric heating unit, comprising a body having 60 recesses formed therein; wire wound cores in said recesses; binding posts secured to said body, the ends of the wire being connected with the binding posts; a cover detachably secured to said body; binding posts secured to said cover, said binding posts adapted to connect with the first named binding posts through fuses; and thermic fuses interposed between said binding posts.

65 3. An electric heating unit, comprising a body having a recess formed in its top; a wire wound core in said recess; binding posts secured to said body, the ends of the wire being connected with the binding posts; a cover

lined with a heat insulating material detachably secured to said body; and binding posts secured to said cover 70 adapted to contact with the first named binding posts.

4. An electric heating unit, comprising a body having recesses formed in its top; wire wound cores in said recesses; binding posts secured to said body, the ends of the wire being connected with the binding posts; a cover 75 lined with a heat insulating material detachably secured to said body; and binding posts secured to said cover adapted to contact with said first named binding posts.

5. A device of the class described, comprising a body; a wire wound core secured to said body; binding posts secured to said body, the ends of the wire on said core being connected with the binding posts; a cover lined with a heat insulating material detachably secured to said body; and binding posts secured to said cover adapted to contact with said first named binding posts. 80

6. A device of the class described, comprising a body; a wire wound core secured to said body; binding posts secured to said body, the ends of the wire on the core being connected to said binding posts; a cover lined with a heat insulating material detachably secured to said body; binding posts secured to said cover adapted to connect with the first named binding posts through fuses; and thermic fuses interposed between said binding posts. 85

7. An electric laundry iron, comprising a body having 90

electric heating means secured thereto; terminals for the electric heating means; a cover lined with a heat insulating material detachably secured to said body; and terminals secured to said cover, said terminals adapted to contact with the first named terminals.

8. An electric heating unit, comprising a body having 95 electric heating means in contact therewith; terminals for said electric heating means; a cover having terminals secured thereto; fuses interposed between said terminals; and moving means secured to the cover and to the body whereby when the cover is attached to the body it will 100 move the terminals secured to the cover into contact with the terminals secured to the body.

9. An electric heating unit, comprising a body having electric heating means in contact therewith; terminals for the electric heating means; a cover having terminals secured thereto; fuses interposed between said terminals; and means secured to the cover and to the body for forcing the terminals secured to the cover into contact with the terminals secured to the body. 110

10. An electric heating unit, comprising a body having 115 electric heating means in contact therewith; terminals for the electric heating means; a cover having terminals secured thereto; thermic fuses interposed between said terminals; and means secured to the cover and to the body for forcing the terminals secured to the cover into contact with the terminals secured to the body.

11. An electric laundry iron comprising an upper and lower member; an electric heater in contact with one of said members; and means secured to both of said members whereby when the members are secured together the 120 circuit is automatically completed.

12. An electric heating unit, comprising a body having recesses, formed in the top thereof; wire wound cores in said recesses; binding posts secured to said body, the ends of the wire on the cores being connected to the binding posts; a cover detachably secured to said body; binding posts secured to said cover; and moving means secured to the cover and to the body whereby when the cover is attached to the body it will move the terminals secured to the cover into contact with the terminals secured to the body. 130

13. An electric heating unit, comprising a body having recesses formed in the top thereof, said body having an inclined face on its outer end; wire wound cores in said recesses; binding posts secured to said body, the ends of the wire on the cores being connected with the binding posts; a cover detachably secured to said body having an inclined face on its outer end adapted to engage the inclined face on the body; binding posts secured to said cover; and thermic fuses interposed between said binding 140 posts.

14. An electric laundry iron, comprising a body having electric heating means in contact therewith; a cover

lined with a heat insulating material detachably secured to said body; and a heat insulating material interposed between the cover and the body.

15. An electric laundry iron, comprising an upper and lower member; electric heating means secured to one of said members; binding posts secured to each of said members, said binding posts adapted to connect with each other through fuses; and fuses interposed between said binding posts.
- 10 16. An electric laundry iron, comprising an upper and lower member; electric heating means secured to said lower member; binding posts secured to each of said members, said binding posts adapted to connect with each other through fuses; and fuses interposed between said binding posts.
- 15 17. An electric laundry iron, comprising an upper and

lower member; electric heating means secured to said lower member; binding posts secured to each of said members, said binding posts adapted to connect with each other through fuses; and thermic fuses interposed between said binding posts. 20

18. An electric heating unit, comprising two members; electric heating means secured to one of said members; binding posts secured to each of said members, said binding posts adapted to connect with each other through 25 fuses; and fuses interposed between said binding posts.

In witness that I claim the foregoing I have hereunto subscribed my name this 1st day of October, 1906.

EARL H. RICHARDSON.
